UNITED STATES PATENT OFFICE.

AUGUST L. SEGELHORST, OF WHITTIER, CALIFORNIA.

CASING HEAD.

Application filed June 12, 1923. Serial No. 444,868.

This invention relates to well drilling equipment and relates particularly to casing heads such as are employed during the drilling of a well.

In the drilling of oil wells, the drill bit frequently strikes pockets of oil under high gas pressure, while penetrating the subterranean strata. It is an infrequent occurrence to strike a gas pocket which blows the entire 10 drill pipe from the well, causing considerable damage, expense, loss of time, and sometimes the loss of life. Considering that the well has been carried successfully to a stratum adjacent to the oil bearing sand, the 15 drill bit upon penetrating this sand will allow oil, if there is sufficient pressure therein, to flow upwardly through the well. Although there are generally indications of the reaching of the oil bearing sand, it sometimes occurs that the presence of oil is not 20 known until the oil flows from the top of the well. It will be readily realized that the oil flowing from the well, and especially if it is under pressure, makes it very inconvenient 25 for the workman to pull the drill shaft, and in addition there is a considerable waste of oil.

It is an object of the invention to provide 30 a casing head which will grip and prevent the drill pipe from being blown from the well.

It is a further object of the invention to provide in a device of this character a means 35 by which the gas may be conducted from the well.

It is a still further object of the invention to provide a casing head of this character which will seal the top of the well, preventing 40 the oil from flowing over the derrick floor, and means for conducting the oil from the well through piping.

The casing head of my invention consists 45 of a body which is screwed to the top end of the well casing. The body has a concentric bore in which is placed a sleeve member which is engaged by means for advancing the sleeve in an axial direction. Below the sleeve is a compressible member which rests in a conical formation included in the bore 50 of the body member, being connected to the sleeve by means of lugs provided on the sleeve. This compressible member is made in segments which are provided with resilient inner faces. During ordinary conditions 55 the compressible member is retained by the sleeve in expanded position, but when a gas

pressure or oil is encountered in the well the sleeve is advanced downwardly in the body by the advancing means. The advancing of the sleeve moves the compressive member 60 from expanded position in the larger diameter of the conical formation into compressed position in the smaller diameter of conical portion. When the compressive member is in this compressed position the 65 resilient faces of the segments are forced tightly around the drill pipe completely encircling it, the adjacent edges thereof being forced together forming a gas and oil tight seal therebetween. The gas or oil may be 70 carried from the casing head through a pipe connected thereto just below the conical portion of the bore in the body.

The especial advantages of the invention and further objects thereof will be made evident hereinafter.

Referring to the drawings which are for illustrative purposes only:

Fig. 1 is a diagrammatic view illustrating the utility of my invention.

Fig. 2 is a vertical sectional view through a device which embodies the features of my invention, the compressible member being shown in non-engaging position.

Fig. 3 is a section taken on a plane represented by the line 3—3 of Fig. 2.

Fig. 4 is a view similar to Fig. 2, but showing the compressible member being shown in engaging position.

Fig. 5 is a section taken on a plane represented by the line 5—5 of Fig. 4.

Fig. 6 is a section taken on a plane represented by the line 6—6 of Fig. 4.

Fig. 7 is an enlarged detail of one of the segments, illustrating more implicitly the 95 construction thereof.

Fig. 8 is a vertical sectional view of another form of my invention which may be used when the drill pipe is considerably smaller than the well casing.

Fig. 9 is a section taken on a plane represented by the line 9—9 of Fig. 8.

Fig. 10 is a view similar to Fig. 9, the compressive member being shown therein in compressed position.

Fig. 11 is a vertical sectional view illustrating a further modification of my invention. The compressive member, in this view, is shown in expanded position.

Fig. 12 is a section taken on a plane represented by the line 12—12 of Fig. 11.

Fig. 13 is a sectional view similar to Fig.

11, the compressible member being shown in compressed position in this view.

Fig. 14 is a section taken on a plane designated by the line 14—14 of Fig. 13.

5 As shown in Fig. 1 a well casing 11 has a casing head 12 of my invention screwed to the top end thereof through which a shaft 14 extends, the shaft 14 being composed of 10 lengths of drill pipe. The shaft 14 is rotated by a rotary table 15 located in derrick 16.

With reference to Figures 2 to 7 inclusive, the casing head 12 consists of a body 20 which has a threaded portion 21 for connecting 15 it to the drill pipe and has an axial bore 22 extended therein. In the upper part of the bore 22 is placed a sleeve 23 which is adapted to be moved axially in the bore 22. The sleeve 23 has engageable means such as 20 teeth 24 externally formed thereon which are engaged by a rotatable ring 25 which is retained in the enlarged portion 26 of the bore 22 by a retaining member 28. The ring 25 may be rotated in either direction by a worm 25 29 in the housing 30 which worm may be turned by a crank which may be placed on the squared portion 31 of the shaft 32 upon which the worm 29 is mounted. Projecting 30 downwardly from the sleeve 23 are lugs 33 which extend through slots 34 in the annular ledge 35, the lower ends of which engage the compressible member 37 in the downwardly diminishing conical portion 39. The member 37 is composed of segments 40 which have 35 resilient inner faces 41 which may be made of rubber or any other suitable compressible material, the faces 41 being of the same curvature as the external diameter of the drill shaft which they are adapted to grip.

40 Any suitable engagement means may be used between the compressible member 37 and the lugs 33, which will allow relational lateral movement therebetween such, as shown in Fig. 7. Projecting upward from 45 each of the segments 40 is a pin 43 having a ball formation 44 at the upper end thereof which fits loosely in a corresponding radial slot 46 formed in the lower end of each of the lugs 33, this engagement being so formed 50 that the lower face of the lug 33 will bear directly against the upper face of the segment 40 when the sleeve is made to advance downwardly, the pin 43 serving only to raise the segments 40. The compressible member 55 37 is provided with an annular spring member 48 which extends through each of the segments 40 holding them outwardly at all times against the face of the conical portion 39 so that they will not interfere with the 60 drill shaft.

During normal drilling conditions the different parts of the casing head 12 are positioned as shown in Figs. 2 and 3. If oil or gas is encountered in the well, the movable parts may be moved to the positions shown

in Figs. 4 and 5, by the operation which will now be described. By rotating the worm 29 with a suitable crank placed on the squared portion 31 of the shaft 32, the ring 25 may be rotated which in turn advances 70 the sleeve 23 downwardly in bore 22. The lower face of each lug 33 will be forced against the top face of each of the segments 40 of the member 37, forcing them downwardly in the conical portion 39. As the compressive member 37 reaches the position shown in Figs. 4 and 5 it becomes forcibly wedged between the wall of the conical portion 39 and the outside surface of the drill pipe, completely encircling the pipe. The inner face 41 being of the same circumferential contour will adhere very accurately to the external circumference of the drill shaft and the face 41 also being of a resilient nature will have a tendency to spread due to the compressive force applied thereto and will constitute a gas or oil tight seal between the different segments 40 as well as around the circumference of the shaft. The oil or gas in the well may then be carried 85 therefrom through pipes which may be screwed in the tapped holes 50 provided in the body 20, as shown.

The upper portion of the sleeve 23 may be formed of upwardly expanding conical contour, as indicated at 55, to accommodate the placing of freely accessible slips (not shown) which are used to hold the drill shaft while adding additional lengths of drill pipe to the shaft or while removing lengths therefrom.

Sometimes in drilling a well a drill pipe which is considerably smaller than the well casing is used. With these circumstances, a casing head as illustrated in Figs. 8, 9 and 10 105 may be used, the parts in these figures being substantially the same as those in the previous figures.

In these figures the drill pipe indicated by the dotted lines 60 is considerably smaller 110 than the well casing and the annular ledge 35 is made wider than that shown in the previous figures so that it presents a bore 61 which is but slightly larger than the drill pipe 60. In the ledge 35 are cut slots 62 115 which are disposed diametrically, providing a distance as indicated by "A" which distance is substantially the same as the diameter of the well casing. The compressible member 37 is made in four segments 40 so that when it is in expanded position the segments 40 will leave spaces therebetween two of which will coincide with the slots as best shown in Fig. 9. By this arrangement it is possible to provide a head which will grip a 120 drill pipe of a much smaller diameter than that of the other head. Also by the provision of the slots 62 and the segmental arrangement shown, an opening for passing a bit into the well is provided, the bit very 125 130

conveniently passing through the slots and between the segments 40 without interference.

In Figs. 11, 12, 13 and 14, is illustrated a further form of the invention. In this modification, I present a device which will accomplish the same result as before but the cost thereof is reduced considerably by simplifying the construction thereof.

In these figures the body 70 provides threads 71 at the lower end for attachment to the well casing, threaded orifices 72 through which oil or gas may be conducted and a bore 73 which provides an angular face 74 between the smaller portion and the larger portion thereof as shown. A compressible member 76 rests in the larger portion of bore 73 which is similar to the compressible members used in the other forms of the invention. The member 76 has a lower face 77, the angle of which corresponds to and is in contact with the face 74 of the bore 73, and has an upper face 78 which is in contact with a corresponding angular face 79 of the sleeve or gland member 80 positioned thereabove in the large portion of the bore 73. The gland member is in threaded engagement with the bore 73 at 82 and may be advanced in either direction by a bar or wrench placed in the holes 83.

By advancing the member 80 downwardly from the position shown in Fig. 11 to the position shown in Fig. 13, the compressible member 76 may be forced from expanded position to compressed position. It will be readily seen that the angular faces 74 and 79 exert a positive inward force on the compressible member 76 when the gland 80 is advanced downwardly and force it into compressed position, Fig. 13, securely against the drill pipe.

From the foregoing it will readily be seen that a great deal of time and labor may be saved by employing my device which will prevent the gas from blowing the drill shaft from the well, and that the working condition during the flowing of oil while the shaft is still in the well may be made better by using my device, as heretofore explained.

I claim as my invention:

1. In a packing organization comprising an upwardly-expanding sleeve carrying circumferential threads, the combination of: a body constituting a casing head which is directly engageable by said sleeve and has a downwardly diminishing opening through which a shaft may extend; a compressible member composed of cooperating and resiliently disposed annular slip segments, also downwardly diminishing within said body, and disposed concentrically with respect to said shaft, and arranged to be compressed into gripping contact with said shaft; and means at the end of said sleeve for compress-

ing said member in said downwardly diminishing opening, the lower end of said sleeve being provided with means causing an inward slippage of said compressible member relatively thereto during compression.

2. In a device of the character described, the combination of: a body adapted to placement upon a well casing and constituting a casing head which is directly engageable by a sleeve and has a downwardly diminishing opening concentric with said casing through which a shaft may extend, said body providing an interior conical formation; cooperating slip members disposed in said conical formation; annular means for holding said slip members resiliently in open arrangement when said slip members are disposed at the large end of said conical formation; and means, comprising said sleeve, for moving said slip members downwardly toward the small end of said formation, so that they will be constricted around said shaft,—the lower end of said sleeve being provided with means facilitating an inward slippage of said cooperating members relatively thereto.

3. In a device of the character described, the combination of: a body adapted to placement upon a well casing and constituting a casing head which is directly engageable by a sleeve and has a downwardly diminishing opening, concentric with said casing, through which a shaft may extend, said body providing an interior conical formation; cooperating slip members disposed in said conical formation, said slip members being adapted to fully encircle said shaft and having resilient facings arranged for engagement with the face of said shaft; annular means for holding said slip members resiliently in open arrangement when said slip members are disposed at the large end of said conical formation; and means, comprising said sleeve, for moving said slip members downwardly toward the small end of said formation, so that they will be constricted around said shaft,—the lower end of said sleeve being provided with means facilitating an inward slippage of said cooperating members relatively thereto.

4. In a device of the character described, the combination of: a body adapted to placement upon a well casing and constituting a casing head which is directly engageable by a sleeve and has a downwardly diminishing opening, concentric with said casing, through which a shaft may extend, said body providing an interior conical formation; cooperating slip members disposed in said conical formation; annular means for holding said slip members resiliently in open arrangement when said slip members are disposed at the large end of said conical formation; moving means, comprising said sleeve member, disposed within said open-

- ing and having engagement with said slip members, and screw means for axially moving said sleeve, so as to advance said slip means downwardly toward the small end of 5 said conical formation, whereupon they will be wedged against said shaft,—the lower end of said sleeve being provided with means facilitating an inward slippage of said cooperating members relatively thereto.
- 10 5. In a device of the character described, the combination of: a body adapted to placement upon a well casing and constituting a casing head which is directly engageable by a sleeve and has an opening, 15 concentric with said casing, through which a shaft may extend, said body providing an interior conical formation; cooperating slip members disposed in said conical formation; means for holding said slip members resili- 20 ently in open arrangement when said slip members are disposed at the large end of said conical formation; a mentioned sleeve member being disposed within said opening and having engagement with said slip mem- 25 bers, said sleeve having screw threads formed upon the exterior thereof; a ring member around said sleeve, said ring member having interior threads engaging said screw threads of said sleeve; and means for rotat- 30 ing said ring member for the purpose of axially moving said sleeve so as to advance said slip members toward the small end of said conical formation, whereupon they will 35 be wedged against said shaft,—the lower end of said sleeve being provided with means facilitating an inward slippage of said co- 40 operating members relatively thereto.
6. In a device of the character described, the combination of: a body adapted to placement upon a well casing and constituting a casing head which is directly engageable by a sleeve and has an opening concentric with said casing through which a shaft may extend, said body providing an interior conical formation; cooperating slip 45 members disposed in said conical formation; means for holding said slip members resili- 50 ently in open arrangement when said slip members are disposed at the large end of said conical formation; a mentioned sleeve member being disposed within said opening and having engagement with said slip mem- 55 bers, said sleeve having screw threads formed upon the exterior thereof; a ring member around said sleeve, said ring member hav- 60 ing interior threads engaging said screw threads of said sleeve; and means for rotat- 65 ing said sleeve, for the purpose of axially moving said sleeve so as to advance said slip members toward the small end of said conical formation, whereupon they will be wedged against said shaft,—the lower end of said sleeve being provided with means facilitating an inward slippage of said co- 70 operative members relatively thereto.
- In testimony whereof, I have hereunto set my hand at Los Angeles, California, this 7th day of June, 1923.

AUGUST L. SEGELHORST.
